PLATFORM SOLE STRUCTURE FOR
FOOTWEAR

Jack Meltzer, New York, N. Y.

Application February 23, 1943, Serial No. 476,834

5 Claims. (Cl. 36—28)

My present invention relates generally to foot-wear and has particular reference to an improved platform sole structure.

It is a general object of my invention to provide an article of footwear whose structural nature is of such a character that it can be manufactured without necessitating the use of a last or any other special machinery or devices and without requiring any "turning" procedure or other difficult steps ordinarily calling for specialized skill. The present improved structure is characterized by its simplicity, and may be manufactured and assembled by a series of simple procedural steps which even the most unskilled person is able to perform without difficulty.

In addition to the great saving in time, cost, and labor which is thus achieved, the present invention has numerous other advantages. It may be employed to produce footwear with a relatively durable outer sole for "street wear," or to produce footwear of the "soft-sole" variety for indoor use. It permits the employment of any selected type or style of "upper." It affords the possibility of using an outer heel of conventional type, or a self-contained padded heel, or no heel at all. It produces an article of footwear which is unusually attractive in appearance, and lends itself readily to innumerable variations in the selection of the color, nature and texture of the materials employed.

One of the main features of an article of footwear constructed in accordance with the present invention, whether it be a sandal, outdoor shoe, slipper, "mule," or any other item, lies in the fact that the sole structure presents a soft and comfortable upper surface to the foot of the wearer. No "sock lining" of any kind is required, the upper surface of the present sole structure being complete in itself, of attractive and finished appearance, and devoid of any free edge portions which might mar its attractiveness, come loose, or otherwise impair its finished workmanlike character. These advantages are not sacrificed by the addition of a heel, nor by the use of an outer relatively tough sole of leather or the like, if the article of footwear is intended for outdoor use. Where an outer heel is used, it is firmly secured in position by nails or equivalent elements which are entirely disposed within the confines of the structure, and the advantages of a "nailed heel" may be achieved without requiring the use of a nail-covering pad and without impairing the softness or comfort of the padded nature of the structure's upper surface.

The present improved platform sole structure 55

consists essentially of two opposed sections which are separately manufactured by simple and inexpensive stitching operations, and which are assembled by the expedient of merely interlacing them. More particularly, the sole structure comprises a bottom section having a marginal flange extending upwards, an opposed top section of corresponding size and contour having a marginal flange extending downwards, a filler fully occupying the space between the sections, and a lacing inter-engaging the flanges to hold their edges in abutment and to retain the entire assembly together as a finished unit.

In carrying out my invention, each section 15 preferably comprises an initial flat flexible blank of sheet material which defines the base of said section, and a tape or equivalent strip having its inner edge stitched to the edge of the base and defining the flange. In the finished structure, the edge of the base lies on the inside of the resultant flange and is thus completely concealed. One of the features of the present invention lies in the employment of a tape which is longitudinally non-stretchable, whereby the resultant flange is self-retained in upright position at the front and rear regions of the section. The necessity for any lasting or other artificially-induced shaping is thus completely dispensed with.

I achieve the foregoing general objects and advantages, and such other objects and advantages as may hereinafter be pointed out, in the manner illustratively exemplified in the accompanying drawings in which:

Figure 1 is a perspective view of the method of producing the bottom one of the present platform sections;

Figure 2 is a view similar to Figure 1 showing the section complete;

Figure 3 is a view similar to Figure 1 illustrating the nature of the procedure involved in forming the top section;

Figure 4 is a detailed cross-sectional view taken substantially along the line 4—4 of Figure 3;

Figure 5 is an exploded view showing the sections of Figure 2 and Figure 3 brought into opposed relationship with certain illustrative filler pieces between them;

Figure 6 is a perspective view of the resultant article for footwear in process of being completely assembled;

Figure 7 is an enlarged cross-sectional view taken substantially along the line 7—7 of Figure 6;

Figures 8, 9, and 10 are fragmentary side views

of illustrative ways of performing the lacing operation;

Figure 11 is a perspective view of a bottom section by itself, prior to completion of an article of footwear, showing the method in which an outer heel may be applied; and

Figure 12 is a fragmentary longitudinal cross-sectional view of the heel portion of a modified construction, showing also the possible use of an outer sole for street wear.

In carrying out the present procedure, I first produce two initially flat flexible blanks of sheet material 20 and 21 (see Figures 1 and 3) substantially conforming in outline to each other and to the shape of a foot. Each of these blanks is formed of leather, cloth, or any other selected flexible material. To the edge of each of these blanks I stitch a non-stretchable tape which extends around the entire periphery and which is relatively stiff transversely so as to define an upstanding marginal flange. In Figure 1 this tape is designated by the reference numeral 22, and in Figure 3 by the reference numeral 23. This tape may be composed of any desired material, such as a braid of fabric, a strip of leather, or the like, the edges being of finished character either by virtue of an inherent selvage, by doubling the material upon itself, or by employing a material such as leather whose free edge is adequately smooth and finished by itself.

Referring to Figure 1, I preferably start the stitching operation at the midportion 24 of the base 20, and it will be observed that the inner edge 25 is secured by stitches 26 to the margin of the base 20, the tape 22 extending around the entire periphery. By virtue of the longitudinal non-stretchability of the tape, it automatically assumes an upright position at the front and rear regions, as indicated at the right in Figure 1, and when the parts have been completely connected the tape is turned into the position shown in Figure 2 so that the edges of the base 20 form an integral marginal flange which lies on the inside of the tape and is thus completely concealed.

The tape 22 is preferably provided with a series of spaced perforations 27, for a purpose presently to be described, but the preformation of the perforations is not absolutely essential.

The resultant section shown in Figure 2 is intended to serve as the bottom section of a platform sole structure of the present character, and this section is in an inverted position as viewed in Figure 2. When the parts are to be assembled, and in the finished article of footwear, this bottom section assumes the position shown most clearly at the lower end of Figure 5, the marginal flange and tape extending in an upward direction. It will be observed that the tape is of uniform height throughout its extent. This is preferable for the bottom section of the structure, but not absolutely essential, as will be pointed out hereinafter.

The braid or tape 23 (Figure 3) is stitched to the base 21 in a similar manner, the inner edge 28 being secured by a row of stitching 29 to the margin of the base blank 21. Here too, the longitudinal non-stretchability of the tape 23 brings about an automatic disposition of the flange in a self-retaining upright position at the front and rear region of the resultant section, and when the tape has been fully applied, it is turned down as shown at the upper end of Figure 5, to provide a flanged top section which is complementary with respect to the bottom section. In the finished structure, it will be observed that the edge

of the base 21 forms an integral marginal flange which lies on the inside of the tape and is thus completely concealed. The tape 28 is also preferably provided with spaced perforations 30.

It will be observed that the attachment of the tape 23 is commenced at a midportion of the base 21, as in the case of the section shown in Figure 1. It is of advantage that the joint, in each case, be disposed along the inner edge of the resultant sole structure, i. e., along the left edge of the right shoe, and along the right edge of the left shoe.

I have illustratively shown the manner in which an upper is associated with the top section during the course of its manufacture. The upper may assume any desired shape or style, and in the accompanying drawings I have shown, merely by way of example, an upper which consists of the two crossing strips 31 and 32 arranged at the forward portion of the structure. These strips are secured to the corresponding edge portions of the base 21 by ordinary stitching. This attachment may be accomplished as a preliminary step, or it may be accomplished (as illustratively shown in the present drawings) by the same row of stitching 30 by means of which the tape 23 is secured to the peripheral edge of the blank 21. In either case, the resultant top section (see the upper part of Figure 5) has the lower edge of the upper (31, 32) engaged beneath the flange defined by the braid or tape 23.

In the simplest embodiment of the invention, the top and bottom sections thus formed are brought together with the flanges directed toward each other, and a filler is introduced between the sections to fully and snugly occupy the enclosed space. This filler may be composed of any desired material, and while it may consist of one piece, it preferably comprises superposed elements including at least one at the top which is relatively soft and at least one at the bottom which is relatively stiff. In Figures 5-7 I have illustratively shown a filler consisting merely of two superposed elements 33 and 34, each being made of soft matted material, the element 33 being adapted to fit snugly into the confines of the top section, the element 34 being adapted to fit snugly into the confines of the bottom section, as indicated in Figure 7.

When the parts are brought together, the final step consists in merely interlacing the flanges or tapes 22 and 23 to bring their edges into abutting relationship. This lacing may be accomplished in any of a variety of ways, depending upon choice. A typical lace 35 is shown in Figure 6, extending in simple manner from one to the other of the perforations 27 and 30. It is most convenient to employ a needle or threading element 36 for this purpose, but it is not necessary that the needle be curved as shown in Figure 6, since the flanges of the two sections are easily manipulable by hand to permit the desired interlacing to be effected. An ordinary lace having a rigid tip at its end, such as is used in an ordinary shoe-lace, may also be used.

The lacing operation may be completed in any desired manner, and I prefer to extend the lacing through a few additional turns and then to cut it off close, whereby the ends lie invisibly within the confines of the structure.

Certain of the advantages of the present invention are most clearly illustrated in Figure 7. It will be observed that the structure has a smooth continuous bottom surface and a smooth continuous upper surface. There is no sock lining

or other extraneous element whose edges would have to be glued down and which might impair the finished appearance of the platform. The structure is staunch and firm, attractive in appearance, and provided with an upper surface which is soft and comfortable. The attractiveness of the item is not marred by the lacing, and, quite to the contrary, the lacing imparts an ornamental effect of unique and pleasing character. The ornamental appearance may be enhanced by properly selecting the material of which the base blanks and tapes are made, and by choosing a lacing of harmonious type and color. Heavy colored cord, a leather thong, or any of a variety of other interesting materials may be employed for this purpose.

Moreover, the invention lends itself readily to numerous variations by virtue of the different modes of lacing which may be employed. For example, in Figure 8, the upper and lower flanges 37 and 38 are secured in abutting relationship by two sets of laces 39 and 40 threaded through the flanges in such a way that a series of crosses results. In Figure 9, laces 41 and 42 are used to provide a slightly different design of successive V-shapes. In Figure 10, laces 43 and 44 are employed to produce a zig-zag effect. One or more laces may be employed for this purpose, and a large number of different ornamental embellishments may be achieved. In each case, the lacing holds the top and bottom sections securely together, with the filler fully occupying the space between these sections, thus uniting the parts into a single structure.

In Figure 11 I have illustrated the adaptability of the present invention to the use (if desired) of an outer heel 45. When such a heel is to be employed, it is applied to the outside of the bottom section prior to the assembly of the parts as shown in Figure 5. A filler element 46 is inserted into the section, and a shank stiffener 47 is applied to this filler. In the illustrated embodiment, the shank stiffener 47 has a portion extending forwardly to reinforce the shank portion of the resultant shoe, and I have also indicated the manner in which a conventional steel reinforcement or arch-supporting element 48 may be carried on the under-side of the stiffener 47, if desired. The heel 45 is secured in position by means of nails or equivalent fastening elements 49 which are driven downwardly through the stiffener 47 and the filler 46 into the heel 45. When this bottom section is brought together with a top section (within which a filler is accommodated, such as the filler 33 of Figure 5) the shank stiffener 47 is completely concealed and embedded within the resultant filler, and in the finished shoe the upper surface of the platform sole structure is just as soft and comfortable as it would be without the presence of the outer heel 45. It will be observed that the outer appearance of the device is thus entirely unaffected by the presence of the heel, that the heel is not precariously glued on but firmly held in place by nails or the like, that there is no nail cover needed, and that the heel of the wearer rests upon a soft pad or cushion and thus finds comfortable support.

In Figure 11 I have also indicated the preferred use of a filler element 50 beneath the padded filler element 46, the element 50 being of relatively stiff character composed, for example, of cardboard or the like.

In Figure 12 I have illustrated a modification which shows how the heel of the wearer may be

elevated without providing an outer heel as shown in Figure 11. In Figure 12, the bottom section consists of a base 51 and an upstanding flange 52 secured to it by stitching 53, the flange 52 being of uniform height throughout its extent, this bottom section being thus substantially the same as that which is shown in Figure 2 and at the lower end of Figure 5. The upper section, however, consists of a base 54 to which a flange 55 is secured by means of stitching 56, the flange 55 being of increased height at the rear end of the structure and diminishing in height gradually toward the front. These two sections are brought together, as before, so that the flanges have their edges in abutment, as indicated in Figure 12, and a lacing 57 extends all around the structure to hold the parts together. On the inside, filler elements 58 are employed to fully occupy the space within the sections, and additional filler material is used in the rear region of the structure to correspond with the increased height of the flange 55. In other respects, the structure of Figure 12 is made and assembled in exactly the manner hereinbefore described in connection with Figure 6. It has the same advantages and the same attractiveness, except that the platform is of increased thickness at the heel region. If desired, the flange of the top section may be of uniform height and the varying height may be provided on the flange of the bottom section, or both flanges may be of non-uniform height depending upon the ultimate appearance desired.

Figure 12 also indicates the manner in which an outer sole 59, of leather or the like, may be adhesively or otherwise secured to the under-side of the present structure, should such outer sole be deemed desirable to increase the wearing qualities of the bottom surface. Such outer sole may also be applied to the structure shown in Figure 11, extending either partly or wholly from the front to the rear of the heeled structure.

One of the outstanding advantages of the present invention lies in its extreme simplicity. From the foregoing description, it will be observed that there is no requirement for any lasting whatsoever, nor for any difficult "turning" procedure or other specialized operations. The entire manufacture and assembly of the structure may be carried out without the necessity for any special skill in the shoe-building art. In fact, the assembly of the parts is so simple, that even the ultimate user may separate the sections and replace them together for the purpose of such replacement of the top or bottom sections as may be desired.

In general, it will be understood that the details herein described are offered merely by way of illustration, for the purpose of explaining the nature of my invention, and that changes in these details may be made by those skilled in the art without departing from the spirit and scope of the invention as expressed in the appended claims.

I claim:

1. A platform sole structure for footwear comprising a bottom section having an upwardly extending integral marginal flange, an opposed top section of corresponding size and contour and having a downwardly extending integral marginal flange, a tape secured to the flange of each section on the outside thereof, the edges of said tapes being in abutting relation, a filler fully occupying the space between said sections, and a lacing interengaging said tapes around the en-

tire periphery of the structure and securing said sections together.

2. A platform sole structure for footwear comprising a bottom section having an upwardly extending integral marginal flange, an opposed top section of corresponding size and contour and having a downwardly extending integral marginal flange, each of said sections comprising an initially flat flexible blank of sheet material, a tape having its inner edge stitched to the flange of each section on the outside thereof, said tape being relatively stiff transversely and longitudinally nonstretchable so that it is self retained in upright position at the front and rear regions of the section, the edges of the tapes of the respective sections being in abutting relation, a filler fully occupying the space between said sections, and a lacing interengaging said tapes around the entire periphery of the structure and securing said sections together.

3. A platform sole structure for footwear comprising a bottom section having an upwardly extending integral marginal flange, an opposed top section of corresponding size and contour and having a downwardly extending integral marginal flange, a tape secured to the flange of each section on the outside thereof, the edges of said tapes being in abutting relation, a filler fully occupying the space between said sections, and a lacing interengaging said tapes around the entire periphery of the structure and securing said sections together, said filler being of smaller area than the bottom section disposing the tape thereof with its lower edge above the bottom of said bottom section.

4. A platform sole structure for footwear comprising a bottom section having an upwardly extending integral marginal flange, an opposed top

section of corresponding size and contour and having a downwardly extending integral marginal flange, each of said sections comprising an initially flat flexible blank of sheet material, a tape having its inner edge stitched to the flange of each section on the outside thereof, said tape being relatively stiff transversely and longitudinally nonstretchable so that it is self retained in upright position at the front and rear regions of the section, the edges of the tapes of the respective sections being in abutting relation, a filler fully occupying the space between said sections, and a lacing interengaging said tapes around the entire periphery of said structure and securing the sections together.

5. A platform sole structure for footwear comprising a bottom section having an upwardly extending integral marginal flange, an opposed top section of corresponding size and contour and having a downwardly extending integral marginal flange, a tape secured to the flange of each section on the outside thereof, the edges of said tapes being in abutting relation, a filler fully occupying the space between said sections, and a lacing interengaging said tapes around the entire periphery of the structure and securing said sections together, said filler comprising superposed elements including a relatively stiff element at the bottom of smaller area than the bottom section disposing the flange of said bottom section turned over said stiff filler element and with the lower edge of the tape thereof above the bottom of the bottom section.

JACK MELTZER.
